UNITED STATES PATENT OFFICE.

ALBERT C. PYLE AND JOHN F. BREWER, OF SEATTLE, WASHINGTON.

HOT-AIR HEATER.

Application filed October 3, 1922. Serial No. 592,104.

To all whom it may concern:

Be it known that we, ALBERT C. PYLE and JOHN F. BREWER, citizens of the United States, residing at Seattle, county of King, 5 and State of Washington, have invented a new and useful Hot-Air Heater; and we do hereby declare that the following is a full, clear, and exact specification, such as will enable others skilled in the art to which it applies 10 pertains to make and use the same.

The invention is a heater with passages in it for causing the gases from the fire to pass back and forth and down and up, which heater and passages are completely surrounded 15 by a casing from which air ducts may be taken.

The object of the invention is to provide a heater that will extract practically all of the heat units from the gases of a fire which 20 is constructed so that it will be absolutely impossible for the gases to escape into a chamber surrounding it.

Another object of the invention is to provide a heater with suitable passages in it 25 for extracting practically all of the heat units from the gases of the fire and which is constructed so that it will be impossible for the gases to escape to a chamber surrounding it; which is of a simple and economical construction. 30

With these ends in view the invention embodies a rectangular shaped heater having the fire box which is lined with fire brick in the center, air passages around the 35 fire box, a damper in the upper part of the rear end and a casing surrounding the fire box and passages.

Other features and advantages of the invention will appear from the following description taken in connection with the drawings, wherein:— 40

Figure 1 is a longitudinal section on the center line of the heater.

Figure 2 is a cross section on line 2—2 of Figure 1.

Figure 3 is a cross section on line 3—3 of Figure 1.

In the drawings we have shown our device as it would appear wherein numeral 1 indicates the fire box, numeral 2 the grate and 50 numeral 3 the ash pit.

The ash pit is constructed in the center of the bottom of the shell 4 which is constructed of a plate bent in the shape of a semicircle 55 at its center which forms the top of the fire box and having its ends extending down-

ward in vertical planes and riveted and welded to a bottom plate 5. A plate 6 is riveted and welded in the end of the shell and this has an opening 7 through it to 60 which the flue is connected. On the inside of the shell and at a short distance from the plate 6 is another plate 8 which also has an opening 9 in it to correspond with the opening 7 in the plate 6. This plate is not as 65 wide as the plate 6 and as it is placed in the center of the shell it will leave perpendicular openings 10 on each side. A damper 11 is hinged in the hole 9 and has a rod 12 projecting from it to which a lever 13 is attached which extends through the front of the outer casing 14 so that it may be operated by hand. The outer casing extends completely around the shell and is constructed so that pipes or ducts may be attached to 70 it in order to carry heat from the heater to any desired locations. The fire box is lined with fire brick 15 on the sides and 16 at the rear end and at the top of the fire brick at the sides are horizontal partitions 16 which 75 extend from the front of the shell to the plate 8 thus causing gases from the fire to pass backward through the passages 17 to the rear of the shell. Between the partitions 16 and the bottom of the shell are other horizontal partitions 18 which extend from the rear end of the shell forward to a point 19 which leaves openings at the front end of the heater for gases to pass downward from the chambers 20 formed between the partitions 16 and 18 to the chambers 21 formed 80 between the partitions 18 and the bottom of the shell.

A fire door 22 may be placed in the front of the shell as shown in Figure 1, an ash door 23 may also be placed in the front of the shell and at the bottom, and clean out doors 24 may be placed in the sides of the shell in order to clean the chambers 20 and 21. It will be seen that plates 25 may be 85 placed between the chambers 21 and 22 and the fire box and ash pit and these plates will extend from the front of the shell to the plate 8, and legs 26 may be placed at the corners of the shell to leave an air space 105 under it.

It will be understood that changes may be made in the construction without departing from the spirit of the invention. One of which changes may be in the shape of the 110 shell, another may be in the number of chambers 20 and 21 used and still another

may be in the location of the clean out doors 24.

The construction will be readily understood from the foregoing description. To use the device it may be assembled as shown and as the fire is started the damper may be opened until it is burning and then as the damper is closed the gases will pass upward as indicated by the arrows 27 and then backward and downward through the chambers 17 as indicated by the arrow 28. They then pass forward through the chambers 20 as indicated by the arrow 29 and then downward into the chambers 21 as indicated by the arrow 30 and backward as indicated by the arrow 31 to the rear of the shell at which point the gases from each side come together in the center and pass upward through the chamber 32 as indicated by the arrow 33 and into the flue as indicated by the arrow 34. It will be seen that as all of the joints of the shell are both riveted and welded it will be impossible for the gases to escape into the chamber surrounding it and also as the gases 25 are forced to pass back and forth practically

all of the heat units will be extracted from them before they reach the flue opening.

Having thus fully described the invention what we claim as new and desire to secure by Letters Patent, is:—

A heater having a rectangular fire-box, a grate for burning either wood or coal, an ash pit under the grate, an ash door in the front of the pit, a fire door above the grate, fire brick lining at the sides and rear of the fire-box, air passages in the sides of the fire-box and ash pit, a central air passage at the rear leading to a flue at the top, a damper in the front of the air passage at the rear, legs supporting the fire-box and air passages so that an air space will be left under them; said fire-box and air passages having their walls constructed of sheet metal and their outer joints riveted and welded; and a chamber surrounding the fire-box and air passages with an opening in the rear through which a flue may be connected to the rear air passage and fire-box.

ALBERT C. PYLE.
J. F. BREWER.
